STRIPING TOOL

Frank B. Hewel, Pittsburgh, Pa.

Application May 10, 1934, Serial No. 724,841

12 Claims. (Cl. 91—62.6)

My invention relates to devices for distributing fluid and the like and has special relation to striping tools for painting lines on automobile bodies, for example.

One object of my invention is to provide a device of the above-indicated character which shall be particularly handy and effective for use in making both horizontal and vertical stripes.

Another object of my invention is to provide a single tool of the class in question adapted to perform all of the necessary or desirable functions in painting lines or stripes on automobile bodies, for example, such as providing an adjustable guide for insuring a straight uniform line, an adjustable width of stripe, manually operated valve control, and a container so adjustable as to permit gravity feed in various operating positions of the striping wheel or cup outlet.

Another object of my invention is to provide a striping wheel or cup that is particularly effective for distributing paint or other fluid by reason of its internal construction including a resiliently mounted loose wheel.

Other and more specific objects of my invention will become evident from the following detailed description taken in conjunction with the accompanying drawings, wherein:

Figure 1 is a view in side elevation of a device constructed in accordance with my present invention when adapted for making horizontal stripes;

Figs. 2 and 3 are views, respectively, in end elevation and in top plan of the device shown in Fig. 1;

Fig. 4 is a sectional view taken along the line IV—IV of Fig. 1;

Fig. 5 is a view in end elevation of the apparatus shown in Fig. 1 when employed for making a vertical rather than a horizontal stripe; and

Figs. 6, 7, 8 and 9 are sectional views showing the details of construction of a certain portion of the apparatus shown in the other figures.

Referring to the drawings, the structure here shown comprises a container or receptacle 1 for fluids such as paint, a striping cup or wheel 2 for applying a line or stripe to a surface such as an automobile body, conduit means 3 communicating with the container 1 and the cup 2, manually operable valve means 4 for controlling the flow of fluid from the container 1, an adjustable guide member 5 for determining the locus or path of the striping cup 2 and a suitable handle member 6.

In Figs. 1, 2 and 3 my device is shown as operative to produce a horizontal stripe on one sur-

face of a body such as 1, an adjacent surface thereof being utilized by the guiding means 5 to determine the path of operation of my device.

The container 1 may be of any suitable character, being shown as cylindrical in form, having a screw plug or cap 10 in the top thereof and an apertured boss or the like 11 in the lower end communicating with portion 28 of the conduit means 3. The cap 10 has a small aperture 25 to permit influx of air and consequent free flow of paint, or other fluid, from the container.

The striping cup or wheel 2 shown in various sections in Figs. 6, 7 and 8 comprises an outer cup proper 12 open at both ends. A shaft or pin 13 extends centrally through the cup 12, having a threaded end 14 inserted in an adjacent portion of the conduit means 3 and having an outer end 15 that is threaded for a purpose to be later set forth.

A three-legged spider 16 is integrally secured internally to the cup 12 near its mid portion and has a sleeve 17 extending toward conduit means 3 and internally threaded to receive a hollow spindle 18 which has a running fit with pin or shaft 13 and to the outer end of which spindle 18 is preferably integrally secured a disc 19 of substantially the same diameter as the outer face of the cup 12. On the free end of spindle 18 a ring nut 20 is threaded whereby the distance that the disc 19 is set or adjusted away from the adjacent face of the cup 12, that is, the width of stripe to be painted, may be selected. This distance is determined by the point on the threaded spindle 18 occupied by the ring nut 20 in bearing tightly or locking against the adjacent end of the sleeve 17 on the spider 16.

In order to provide a continuous and uniformly smooth flow of paint or the like, a four-legged wheel 21, dished at the center, as best shown in Fig. 9, is shown as loosely mounted on the spindle 18 between the spider 16 and the disc 19 within the cup 12. Furthermore, a pair of helical springs 22 and 23 bear against opposite sides of the wheel 21 at the dished portion, whereby it is resiliently adjustable longitudinally as may be necessary during the operation and adjustment of the striping cup. Thus, the faces or ends of the spring 22 respectively bear against the wheel 21 and the disc 19, while the faces or ends of the spring 23 respectively bear against the wheel 21 and the spider 16.

In making the above-described adjustment of the width of stripe to be painted, the dished wheel 21 automatically centers the springs 22 and 23 as the springs are compressed or released. It

should be noted that two or more wheels 21, suitably spaced by such springs, may be employed, if desired.

To secure in position the entire cup member from the spindle 18 to the cup 12 and including the disc 19, a knurled nut 24 may be screwed on the threaded outer end 15 of the pin or shaft 13 whereby the entire cup assembly rotates around the stationary pin or shaft 13, being held in the desired axial position by reason of the disc 19 bearing against the inner face of the nut 24 and the free end of the spindle 18 bearing against the adjacent surface of the conduit means 3.

The conduit means 3 comprises a longitudinally apertured member 28, roughly square in section, which has a pivotal miter joint 30 with a second longitudinally apertured portion 29, likewise roughly square in section and of T-shape in plan (see Fig. 3). A counter-sunk bore or depression 31 in the portion 29 at the miter joint 30 has a running fit with a corresponding annular flange 32 on portion 28, a suitable washer or gasket 33 being provided through which extends a pin 34 substantially at right angles to the miter joint, one end of which is secured by a small pin 35 in the T-shaped portion 29, whereas the other end is threaded and is provided with a gasket 36 and a knurled thumb nut 41 to lock the two portions 28 and 29 of the conduit means 3 in any desired angular relation.

A small tube 37 is fitted into the outer side or top of the T-shaped portion 29, communicating with the aperture therethrough, and extends within the cup 12 at one side thereof to feed paint 35 or the like into the cup.

It will be noted that the T-shaped portion 29 has its central leg 38 extending toward the other portion 28 of the conduit means 3 to form the above-noted miter joint 30 therewith, whereas one lateral extension 39 of the portion 29 is associated with the valve means 4, the other lateral extension 40 being associated with the guiding means 5, as subsequently set forth in more detail.

By reason of the provision of the above-noted pivotal miter joint 30, the container 1 may be secured by the knurled nut 41 in the position shown in Figs. 1 to 4, for example, to insure a gravity feed of paint or the like from the container 1 through conduit means 3 into the striping cup 2 when the latter is operating on a horizontal surface, for example. However, if the device is to be used in making a stripe on a vertical surface, then in order to insure the desired gravity feed from the container 1, this container, by reason of the miter joint 30, may be rotated, for substantially 90°, into the position shown in Fig. 5, in which case the container is again on a higher plane than the striping cup 2, thus insuring the desired gravity feed. While the two positions of the container 1 illustrated in Fig. 1 and Fig. 5, for example, will be those most generally utilized, it will be appreciated that various other positions of the container may be utilized if and when necessary, depending upon the operating position of the striping cup 2, in order to insure the desired gravity feed of paint or the like thereto. In whatever position is selected, the tightening of the thumb nut 41 will insure holding the conduit parts in the desired relation. It will be appreciated that this natural or inherent feed, being universal (within wide limits), is of prime importance.

The valve means 4 may comprise a suitable pointed pin or needle valve 44 in the T-shaped portion 29 of the conduit means 3, passing

through a gasket 43 into the passageway in that portion to thereby control the flow of paint or the like from the container 1 to the striping cup 2. A link 45, associated with the needle valve 44 by means of a pin 46, and a second or upper link 42, associated with the portion 45 by a pin 48, serve to properly connect the needle valve 44 with a suitably curved thumb lever 47, whereby the valve may be readily operated without binding. The valve 44 and thumb lever 47 are biased to the illustrated closed position by means of a suitably bent wire spring 49 which operates between the thumb lever 47 and the T-shaped portion 29 of the conduit means 3. In order to provide the proper intermediate fulcrum for the thumb lever 47, a pedestal or pillar 50, pivoted to lever 47 by pin 51, is secured to a proper point in the T-shaped portion 29 of the conduit means 3, whereby pressure by the thumb or otherwise on the thumb lever 47 when the handle 6 is grasped by the fingers, for example, causes the needle valve 44 to be raised upwardly, and a release of the thumb lever 47 as previously noted, by reason of the provision of the spring 49, causes the needle valve 44 to assume its illustrated closed position.

The guiding means 5 comprises a rod 52 extending through the lateral extension 40 of the T-shaped portion 29 of conduit means 3, this rod having a double bend therein comprising portions 54 and 55 bent at successive right angles, the portion 55 terminating in a small roller 56 operating on a reduced portion 57 of the end member 55, whereby the roller 56 may, with a minimum of friction, roll along a portion of the body 7 to be striped, thereby guiding the striping cup 2 and insuring a straight line being traced thereby.

By reason of the adjustability of the rod 52 because of the provision of a screw 53 securing it to its desired position within the lateral extension 40, a relatively wide range of operation of the cup 2 is provided in conjunction with proper guiding thereof by means of the illustrated guiding means 5.

The handle 6 may be of any suitable character, being secured by a bent rod 58 to the lateral extension 39 of the T-shaped portion 29 of conduit means 3.

The operation of my device may be set forth as follows, reference being had, for example, to Figs. 1, 2 and 3.

The receptacle 1 having been supplied with suitable paint, the handle 6 is grasped, preferably by the four fingers, and the guiding means 5 is adjusted to its proper position on an adjacent surface to that to be striped. The striping tool is then passed along the surface to be marked, the valve means 4 being operated by means of the thumb lever 47 to permit paint to flow out of the cup 12 between it and the disc 19, thereby forming a line of uniform width, which width may be varied by means of the ring nut 20, as previously described. When it is desired to stop the flow of paint, it is merely necessary to release the thumb lever 47 whereupon spring 49 closes needle valve 44.

In the event that a vertical surface is to be operated on, the container 1 is moved to the position shown in Fig. 5, and the device is operated similarly to the manner previously set forth to produce either a horizontal or a vertical stripe on such vertical surface. The provision of the floating or loose wheel 21 in the striping cup 2 insures in all cases a uniform continuous flow of paint without flooding.

It will be seen, therefore, that I have provided a

striping tool which is capable of performing all of the necessary or desirable functions with respect to satisfactorily striping an automobile body or the like on either horizontal or vertical surfaces and that a free flow of paint is provided at all times by reason of the adjustability of the paint container to a position insuring a gravity feed of paint in various operating positions of the striping cup. Suitable adjustable guiding means are provided to insure a straight line, the width of which may be varied as desired, and a mere release of a thumb lever insures the stoppage of the flow of paint.

I do not wish to be restricted to the particular structural details or arrangement of parts illustrated herein, inasmuch as various modifications thereof may be effected without departing from the spirit and scope of my invention. I desire, therefore, that only such limitations shall be imposed as are indicated in the appended claims.

I claim as my invention:

1. A device for distributing fluid comprising rotatable outlet means, a container for said fluid, and a conduit communicating with said container and said outlet means, said conduit having an adjustable miter joint, and means for securing the parts of said joint in different relative fluid-feeding positions.

2. A device for distributing marking fluid by gravity comprising rotatable outlet marking means, a container for said fluid, a conduit communicating with said container and said outlet means, said conduit having a miter joint with its parts relatively rotatable, and means for setting said joint in pre-selected fluid-feeding positions dependent upon the use of said outlet means for producing a horizontal or a vertical mark.

3. A device for distributing fluid comprising a container for fluid, a conduit connected thereto and having a T-shaped portion, outlet means mounted on the top of said portion to communicate with said container through one leg of said T-shaped portion, a valve operable in said portion and having an operating member mounted on another leg thereof, and a guide for said outlet means mounted on the third leg of said portion.

4. A device for distributing fluid comprising a container for fluid, a conduit connected thereto, outlet means mounted on one end of said conduit to communicate with said container, a valve operable in said conduit near said end and having an operating member mounted thereon, and a guide for said outlet means also mounted on said conduit near said end, said conduit end having an adjustable miter joint with the other portion of said conduit to insure gravity feeding through said valve to said outlet means in various fluid-distributing positions thereof.

5. A device for distributing fluid comprising a container for fluid, a conduit connected thereto and having a T-shaped portion, outlet means mounted on the top of said portion to communicate with said container, a valve operable in said portion and having an operating member mounted on one lateral extension thereof, and a guide for said outlet means mounted on the other lateral extension of said portion, the central member of said T-shaped portion having an adjustable miter joint with the remainder of said conduit.

6. A device for distributing fluid comprising a container for fluid, a conduit connected thereto and having a T-shaped portion, an outlet wheel rotatably mounted on the top of said portion, a tube extending from the adjacent end of said conduit into said wheel, a valve operable in said portion and having an operating member mounted on one lateral extension thereof, a handle member secured to said extension, and a guide for said wheel adjustably mounted on the other lateral extension of said portion.

7. A device for distributing fluid comprising a container for fluid, a conduit connected thereto and having a T-shaped portion, an outlet wheel rotatably mounted on the top of said portion, a tube extending from the adjacent end of said conduit into said wheel, a valve operable in said portion and having an operating member mounted on one lateral extension thereof, a handle member secured to said extension, and a guide for said wheel adjustably mounted on the other lateral extension of said portion, the central member of said T-shaped portion having an adjustable miter joint with the remainder of said conduit.

8. A rotatable device for distributing fluid comprising a cup-shaped member having a spindle extending therethrough, a disk mounted on said spindle at an open end of said cup-shaped member, and a wheel loosely mounted on a portion of said spindle within said cup-shaped member.

9. A rotatable device for distributing fluid comprising a cup-shaped member having a spindle extending therethrough, a disk mounted on said spindle at an open end of said cup-shaped member, a wheel loosely mounted on a portion of said spindle within said cup-shaped member, and resilient means for longitudinally acting on said wheel.

10. A rotatable device for distributing fluid comprising a cup-shaped member having a spindle extending therethrough, a disk mounted on said spindle at an open end of said cup-shaped member, a wheel loosely mounted on a portion of said spindle within said cup-shaped member, and a plurality of helical springs surrounding said spindle and respectively bearing on opposite sides of said wheel.

11. A rotatable device for distributing fluid comprising a cup-shaped member having a spindle extending therethrough, a disk mounted on said spindle at an open end of said cup-shaped member, means for adjusting the distance between said open end and said disk, a wheel loosely mounted on a portion of said spindle within said cup-shaped member, and a plurality of helical springs surrounding said spindle and respectively bearing on opposite sides of said wheel.

12. A rotatable device for distributing fluid comprising a cup-shaped member having a spider internally secured thereto, a spindle extending through said member and spider, a disk mounted on said spindle at an open end of said cup-shaped member, a wheel having a dished portion loosely mounted on said spindle between said spider and said disk, and a plurality of helical springs surrounding said spindle and respectively bearing against opposite sides of the dished portion of said wheel.
